(57) **CLAIM**

The ornamental design for a display screen or portion thereof with graphical user interface showing a soil tester as shown and described.

DESCRIPTION

FIG. 1 shows a display screen or portion thereof with graphical user interface showing a soil tester of the new design;

FIG. 2 is a front view showing the display screen or portion thereof with graphical user interface showing a soil tester according to a first embodiment; and,

FIG. 3 is a front view showing the display screen or portion thereof with graphical user interface showing a soil tester according to a second embodiment.

The outermost broken lines shown in the figures are for the purpose of illustrating portions of the display screen or portion thereof with graphical user interface showing a soil tester and form no part of the claimed design.

1 Claim, 3 Drawing Sheets
